FACEPLATE ARRANGEMENT

Basil E. Jones, Flossmoor, Ill., assignor to The
Pullman Company, Chicago, Ill., a corporation
of Illinois

Application September 4, 1942, Serial No. 457,288

9 Claims. (Cl. 105—21)

This invention relates to railway cars and more particularly to the faceplate arrangement at the passageway between adjoining cars.

The invention has for its principal object the provision of means for excluding weather from the joint between faceplates of adjoining cars formed by the contacting surfaces of the respective faceplates.

The invention contemplates the use of complementary gutters disposed immediately beneath the contacting surfaces of adjoining faceplates above the passageway between cars, each secured at one end to the respective faceplates and arranged to abut one against the other in a vertical plane at an angle to the line of contact between the adjoining faceplates and intersecting such line of contact substantially at the center of the passageway with spring means maintaining contact between the gutters.

The foregoing and other objects are attained by the mechanism illustrated in the accompanying drawings in which—

Fig. 1 is an end elevational view of a railway car with the lower portion broken away and provided with a passageway faceplate equipped with the weather excluding device of this invention;

Fig. 2 is an enlarged plan sectional view taken on the line 2—2 of Fig. 1 illustrating the weather excluding members of adjoining cars disposed in abutting relation and showing the line of contact between the members to be at an angle to the line of contact between adjoining faceplates;

Fig. 3 is a detail view of the spring device for maintaining contact between adjoining weather excluding members and showing the faceplate to which it is attached in section taken on the line 3—3 of Fig. 2;

Fig. 4 is a detail sectional view taken on the line 4—4 of Fig. 1 through the weather excluding trough and showing the manner of attachment for the spring engaging member; and

Fig. 5 is a longitudinal sectional view through the passageway of adjoining cars taken as indicated on the line 5—5 of Fig. 1 and showing the faceplates of the respective cars in contact and the engagement between the opposed weather excluding troughs.

In the drawings 10 represents a railway car having an end wall 11 provided with an end doorway 12. A passageway faceplate 13 is disposed in spaced relation to the end wall and is provided with hinged wing members 14 pivotally supported therefrom to provide means of attaching and supporting a streamlining diaphragm 15 about

the perimeter of the car. The streamlining diaphragm is secured to the faceplate and wing members and the car end by means of clamping devices 16 leaving the diaphragm imperforate. 5 A bellows fold diaphragm 17 is also disposed between the faceplate and car end to provide a weather-tight passageway and is secured by means of Z-shaped attaching frames 18 and 19 respectively. The faceplate is maintained in spaced relation to the car end wall against the buffing action of associated cars in a train through the medium of an upper buffer stem 20 pivotally secured to the faceplate by means of bracket 21 and engaging against a buffing spring 15 22 adapted to urge the upper portion of the faceplate outwardly and by lower buffer stems 23 pivotally secured as at 24 to buffer plate 25 and engaging a buffing device (not shown) to urge the faceplate outwardly away from the car end wall. 20 It will be seen that contact between faceplates of adjoining cars is assured by these upper and lower buffering devices and buffering shocks between cars absorbed while the respective faceplates are at all times maintained in proper spaced relation to the end walls of the cars. Thus a completely enclosed passageway is provided from one car to the other through the associated diaphragms 17 with only the joint 27 between the adjoining faceplates intervening. Footplates 26 25 and 28 provide a walkway through the passageway. 30 It has been found that the joint 27, even though the contacting surfaces of the faceplates, might be covered with fibrous material to act 35 as a seal, failed fully to exclude the weather and permitted water and dirt to continue to leak through and drip from the lower portion of the joint into the passageway onto passengers passing therethrough and caused a wet and slippery 40 condition of the footplates so that it created a hazard to persons walking through from one car to the other. In order to eliminate this condition, trough shaped gutters 30 are utilized beneath the joint to receive any water or dirt dripping therefrom and which are adapted to pass it off at either side. One gutter is used on each faceplate at each end of each car and the respective gutters are pivotally connected to their 45 associated faceplate at the opposite side of the passageway from the gutter at the other end of the car so that individual cars may be coupled together with either end of one car associated with either end of another car without the necessity of maintaining any particular relation between cars to be coupled. 50 55

Each gutter 30 comprises a channel member having one flange 31 relatively higher than the other flange 32 and closed at one end as 33 with the other end 34 remaining open. The gutter is pivotally supported at its closed end from flange 29 on the faceplate by means of flanged bracket 35 attached to the flange of the faceplate by means of rivets 36. The bracket 35 comprises a jaw into which the gutter is fitted and a headed pin 37 is then passed through the assembly and secured by a cotter 38. The jaws of the bracket 35 are spaced the depth of the gutter as best shown in Fig. 5 and the gutter itself is provided with a sleeve 39 which is welded into the corner of the closed end of the gutter and through which the pivot pin 37 passes. The sleeve 39 provides a full length bearing for the pivot pin and serves as a spacer from the bottom of the gutter to the top jaw of the supporting bracket. The flange 31 is of greater height to afford increased contacting area between the opposed faces of gutters on associated cars and provide for relative movement between the faceplates as the cars negotiate curves and various elevations and depressions in the track. The end wall 33 forming a continuation of the flange 31 at the closed end of the gutter extends around the sleeve 39 as best shown in Figs. 2 and 5 before sloping down to the level of rear flange 32. The flange 31 as best illustrated in Fig. 2 is disposed at an angle to the rear flange 32 so that the joint formed by the contacting flanges 31 of gutters on associated cars is always at an angle to the joint formed by the adjoining buffering surfaces of the faceplates above the gutters regardless of whether the faceplates may be centered with respect to each other as when the cars are on a straight track or when they are displaced laterally on curved sections of track or when they may be disposed at an angle.

It will be seen that the opposed gutters of associated cars provide troughs extending substantially the full width of the passageway and that their line of contact 40 being at an angle to the line of contact 41 between the faceplates as best seen in Fig. 2, the only water which might drip directly onto the joint formed by the contacting flanges 31 from the joint between the faceplates above the gutters can only occur at that point where the line of contact between the gutters and that of the faceplates intersects, thus minimizing the possibility of water and dirt getting through to the passageway. All of the water dripping into the gutters 30 from between the faceplates will be guided by the flanges 31 and 32 of the respective gutters to run to the open end of each gutter at opposite sides of the passageway where it is drained closely adjacent the passageway diaphragm 17. The contacting flanges 31 of gutters on adjoining cars are at all times maintained in engagement by means of springs 45 engaging the free end of each gutter to urge them outwardly in a direction whereby opposed gutters of associated cars exert pressure one against the other at all times. The free end of each gutter which comprises the open end 34 is supported in a bracket 46. This bracket comprises a U-shaped bent plate having depending flanges 47 and 48 for attachment to flange 49 of the face plate to provide a closed slot 42 in which the movement of the supported end of the gutter due to relative movement between the associated cars is adapted to be accommodated. The attachment of bracket 46 to flange 49 is had by means of rivets 51 and 52 with the bracket disposed on the opposite side of the flange from the passageway. A channel

shaped member 50 turned on its side with the open face turned to the rear or toward the car body, is secured to each gutter to provide an extension for supporting the free end of the gutter in the slot 42. An angle member 53 is secured to the web of the gutter member adjacent the open end thereof by means of rivets 54 and by welding and the channel shaped extension member 50 is secured with its web disposed in abutting relation to the depending flange of the angle by means of rivets 55 and by welding. All of the welds between the various members are indicated by the numeral 56. The member 50 extends into the slot 42 to support the free end of the gutter in the bracket 46 and is provided with an inwardly projecting stud 57 disposed in opposed relation to a similar stud 58 secured in the rear wall of the slot. Spring 45 is supported on these two studs in a manner to exert pressure between the bracket 46 and the extension member 50 to force the gutter outwardly with the flange 49 of the faceplate acting as an outer limit of movement when the web of member 50 comes in contact with the edge of the flange. When the cars are uncoupled the web of member 50 will be in contact with the edge of flange 49 with the spring 45 expanded but when the cars are coupled the spring will be compressed and the extension member spaced from the flange, an amount depending upon the relative movement between the associated cars but the spring 45 will insure contact at all times between adjoining gutters so that a trough beneath the top of the faceplates to catch any water or dirt dropping therefrom is always insured.

From the foregoing, it will be seen that a faceplate has been provided which is equipped with a trough for catching water and dirt dropping from the joint between adjoining faceplates before it can fall on passengers going through the passageway between cars and which is automatically operable to engage a similar trough on an adjoining car so equipped without the necessity for any adjustment whatever and which does not cause any interference when a car equipped with such a trough is coupled to a car not so equipped.

What is claimed is:

1. A railway car passageway including a faceplate having an upper surface adapted to be disposed in engagement with a similar surface of an adjoining faceplate thereby to form a joint, a trough member pivotally secured at one side of the passageway to said first faceplate and extending beneath said joint part way of the width of the passageway and supported from said faceplate at the other side of the passageway, spring means engaging the trough at said last named side, and a similar trough on said adjoining faceplate adapted to extend beneath said joint the remaining width of the passageway, said troughs being maintained in engagement by said spring means.

2. A railway car passageway including a faceplate having an upper surface adapted to be disposed in engagement with a similar surface of an adjoining faceplate thereby to form a joint, a trough member pivotally secured at one side of the passageway to said first faceplate and supported at the other side of the passageway from said faceplate for relative movement thereto, spring means engaging the trough at said last named support, and a similar trough and spring means on said adjoining faceplate pivotally secured to and supported therefrom at respectively opposite sides from the first faceplate and adapt-

ed to be disposed in opposed relation to the first trough, said spring means cooperatively maintaining the troughs in operative engagement beneath said joint with the engaging surfaces of the troughs at an angle to the engaging surfaces of said faceplates.

3. A faceplate having a buffing surface, a trough adapted to be disposed beneath said surface, a bracket secured to the faceplate at one side for pivotally supporting one end of said trough, a bracket secured to the faceplate at the other side for supporting the other end of the trough, spring means associated with the last named bracket adapted to urge the trough outwardly of said buffing surface, and an extension member secured to the trough adapted to engage said last named bracket and be engaged by said spring means, said trough comprising an inverted channel shaped member having a closed end and an open end and an upstanding flange on each side, one of said flanges being relatively higher than the other.

4. A faceplate having a buffing surface, a trough adapted to be disposed beneath said surface, a bracket secured to the faceplate at one side for pivotally supporting one end of said trough, a bracket secured to the faceplate at the other side for supporting the other end of the trough and spring means associated with the last named bracket adapted to urge the trough outwardly of said buffing surface, said trough comprising an inverted channel shaped member having a closed end and an open end and an upstanding flange on each side, one of said flanges being relatively higher than the other.

5. A faceplate having a buffing surface, a trough adapted to be disposed beneath said surface, a bracket secured to the faceplate at one side for pivotally supporting one end of said trough, a bracket secured to the faceplate at the other side for supporting the other end of the trough and spring means associated with the last named bracket adapted to urge the trough outwardly of said buffing surface.

6. A drip trough for railway car passageway faceplates comprising an inverted channel having a closed end and an open end, upstanding side flanges on the trough, one of said flanges being relatively higher than the other to provide an extended contacting area between adjoining

troughs, said higher flange being disposed at an angle to the other flange to provide a trough substantially wider at one end than at the other, a bracket at one end of the trough for pivotally connecting the trough to a faceplate, an extension member at the other end of the trough and engaging a bracket slidably to support the trough for horizontal swinging movement with respect to a faceplate, and spring means in said last

5 named bracket for urging the trough in one direction.

7. A drip trough for railway car passageway faceplates comprising an inverted channel having a closed end and an open end, upstanding side flanges on the trough, one of said flanges being disposed at an angle to the other flange to provide a trough substantially wider at one end than at the other, a bracket at one end of the trough for pivotally connecting the trough to a faceplate, an extension member at the other end of the trough and engaging a bracket slidably to support the trough for horizontal swinging movement with respect to a faceplate, and spring means in said last named bracket for urging the trough in one direction.

8. A drip trough for railway car passageway faceplates comprising an inverted channel having a closed end and an open end, upstanding side flanges on the trough, one of said flanges being disposed at an angle to the other flange to provide a trough substantially wider at one end than at the other, a bracket at one end of the trough for pivotally connecting the trough to a faceplate, a bracket slidably to support the trough for horizontal swinging movement with respect to a faceplate, and spring means in said last named bracket for urging the trough in one direction.

9. A drip trough for railway car passageway faceplates comprising an inverted channel having an open end, upstanding side flanges on the trough, a bracket at one end of the trough for pivotally connecting the trough to a faceplate, a bracket slidably to support the other end of the trough for horizontal swinging movement with respect to a faceplate, and spring means in one of said brackets for urging the trough in one direction.
